[57] **CLAIM**

The ornamental design for a skateboard or snowboard mounting rack and a separate wall protecting strip, as shown and described.

DESCRIPTION

FIG. 1 is a front elevational view of the skateboard or snowboard mounting rack and an attached wall protecting strip showing my new design. A skateboard, which is not a part of the invention, is shown in broken lines inserted into the rack and against the wall protecting strip.

FIG. 2 is a front elevational view of the rack;

FIG. 3 is a rear elevational view of the rack;

FIG. 4 is a right side elevational view of the rack, the left side elevational view being a mirror image thereof;

FIG. 5 is a top plan view of the rack;

FIG. 6 is a bottom plan view of the rack.

FIG. 7 is a right side elevational view of the wall protecting strip, the left side elevational view being a mirror image thereof; and,

FIG. 8 is a top plan view of the wall protecting strip the bottom plan view being a mirror image thereof.
